UNITED STATES PATENT OFFICE.

JOSEPH REES, OF NEW YORK, N. Y.

DESIGN FOR A FINGER-RING.

SPECIFICATION forming part of Design No. 22,193, dated February 7, 1893.

Application filed December 22, 1892. Serial No. 456,095. Term of patent 3½ years.

To all whom it may concern:

Be it known that I, JOSEPH REES, a citizen of the United States, residing at New York, in the county and State of New York, have 5 invented and produced a new and original Design for Rings, of which the following is a specification, reference being had to the accompanying drawings.

This design has for its object to provide a 10 novel and ornamental finger ring and it consists in a finger ring provided with a setting and having at each side the representation of a spread eagle interposed between the shank of the ring and the setting, so that the latter 15 appears as supported by the representation of the spread eagle.

The design is illustrated by the accompanying drawings in which

Figure 1, shows a side elevation of the ring.
20 Fig. 2, is a view looking through the ring.

In the drawings the letter A indicates the shank of the ring and B is the setting. At

the junction between the shank and the setting is an ornament C in the form of the conventional representation of a spread eagle 25 resting on a representation D of the globe all in such manner that the setting appears as supported by the representation of the spread eagle.

The design provides a novel and ornamental 30 ring which presents a distinguishing and characteristic appearance to the eye.

What I claim as new and desire to secure by Letters Patent is

The design for a ring substantially as shown 35 and described.

In witness whereof I have hereunto set my hand in the presence of two subscribing witnesses.

JOSEPH REES.
